UNITED STATES PATENT OFFICE.

GEORGE E. TURNER, OF FALLS CITY, NEBRASKA.

COMBINED SELF-PROPELLED MACHINE AND PORTABLE TRACK THEREFOR.

1,069,045.

Specification of Letters Patent.

Patented July 29, 1913.

Application filed May 27, 1912. Serial No. 699,986.

To all whom it may concern:

Be it known that I, GEORGE E. TURNER, a citizen of the United States, residing at Falls City, in the county of Richardson and 5 State of Nebraska, have invented certain new and useful Improvements in Combined Self-Propelling Machines and Portable Tracks Therefor, of which the following is a specification.

10 My invention relates to combined traction engines and portable tracks for same, or to self propelling excavating machines and tracks therefor; the object of the invention being to provide a safe and reliable passage 15 for such machines or engines over irregular, soft or slippery grounds.

The invention comprises in addition to the above named elements, mechanical or power-driven means for shifting the track 20 forwardly after each progressive movement of the machine.

In order that the invention may be fully understood, reference will now be made to the accompanying drawings, in which:

25 Figure 1 is a plan view of a track constructed and assembled in accordance with my invention, having mounted thereon the wheeled frame of a tractor excavating machine, said machine being shown diagrammatically. Fig. 2 is a side elevation of the track and machine frame, or truck, shown in Fig. 1. Fig. 3 is a detail in section on line III—III of Fig. 2. Fig. 4 is a detail in section on line IV—IV of Fig. 1. Fig. 5 30 is a detail in section on line V—V of Fig. 1.

Referring to the drawings, 1 and 2 designate the track sections, each of which is shown as composed of a plurality of longitudinally-disposed wooden beams 3, tied together with cross-bolts 4. The forward end of each section is somewhat pointed, as shown, and is protected by a metal strap 5.

As four is the usual number of carrying wheels on a traction engine, four track sections will ordinarily be employed, one for each wheel, as shown. The pointed end of one section is connected with the square end of the adjacent section, preferably, by 45 means of two coupling plates 6 and vertical bolts 7 and 8 (Fig. 4). The single bolt 8 through the pointed end of section 2, constitutes a pivotal connection between the sections and permits the track to be laid on 50 curves or turns of different radii, as will 55 readily be understood without illustration.

The frame 9 in the drawing represents the frame of a traction-engine or excavator, such for instance, as shown in my copending application Serial No. 693,261, parts not germane to the invention being omitted. 60 The traction wheels 10 and steering wheels 12 rest on the respective track sections.

Secured across the underside of the frame 9, close to the wheels 10 and 12, are two pairs of beams 13, which extend beyond the frame and support four lifting jacks, as seen on Fig. 1. These jacks are desirably of the steam or hydraulic type. As shown, each comprises a cylinder 14, having a base 15 bolted between beams 13, a piston 16; a 65 stem 17; and a pedestal or foot 18, secured to the stem by a pivot 19. I also provide for each jack, a wooden shoe 20, of suitable dimensions. These shoes may be kept either separate from the parts 18, or attached 70 thereto.

21 and 22 designate motive fluid, inlet and exhaust-pipes, connected with each jack cylinder and controlled by valves 23.

A transverse shaft 24 is journaled in 80 brackets 25 on frame 9. On said shaft are a sprocket-wheel 26 and two drums 27, the latter being arranged above the centers of the track sections. A slot 28 is cut lengthwise in each rear track section, to receive 85 a cable 29, one end of which is tied to the bolt 4, the cable passing above the slot and being fastened to its respective drum 27.

The operation is substantially as follows: After the wheels 10 and 12, and frame 9 90 have moved leftwardly as far as the track sections permit, they are stopped and the jacks are operated to lift the machine bodily from the tracks. The shaft 24 is then rotated by suitable power (not shown) to 95 cause the cables 29 to pull the track sections forward until their rear ends are close to the wheels 12. The valves 23 are then operated to relieve the jacks and lower the machine until the wheels 10 and 12 again 100 rest upon the track sections; further upward motion of the pistons will lift the shoes 20 clear off the ground if said shoes be attached to the plungers. The traction engine or excavating machine then proceeds again 105 until its wheels approach the forward ends of the track sections, when the aforesaid operations may be repeated.

During the drawing forward of the rear track sections 2, they may be guided to 110

right or left by shifting the front ends of the forward sections 1, the latter thus guiding the former.

Having thus described my invention what I claim and desire to secure by Letters Patent, is:

5. In combination with a track, a frame having traction wheels mounted on said track, a pair of spaced beams at each end of the frame the ends of which extend beyond the sides of the frame, a cylinder at each end of each pair of beams secured in the space between the latter, a piston in each cylinder, a stem depending from each piston, an individual foot for each stem pivoted to the lower end of the latter, and valve controlled motive fluid inlet and exhaust pipes connected with the cylinders.
10. In combination with a track, a frame having traction wheels mounted on said track, a cylinder secured at each corner of the frame, a piston in each cylinder, a stem depending from each piston, an individual foot for each stem pivoted to the lower end
15. In combination with a track, a frame having traction wheels mounted on said track, a pair of spaced beams at each end of the frame the ends of which extend beyond the sides of the frame, a cylinder at each end of each pair of beams secured in the space between the latter, a piston in each cylinder, a stem depending from each piston, an individual foot for each stem pivoted to the lower end

of the latter, and means to admit and exhaust motive fluid to and from said cylinders.

3. In combination with a track composed of oppositely disposed sections, a frame having traction wheels mounted on said sections, each section having a longitudinal slot and being composed of a plurality of longitudinally disposed abutting beams, cross-bolts connecting the beams, one of said cross-bolts of each section extending above the bottom of the slot thereof, a cable for each section having one end disposed in said slot thereof and secured to the last named cross-bolt thereof, and winding means on the frame secured to the opposite end of each cable.

In testimony whereof I affix my signature, in the presence of two witnesses.

GEORGE E. TURNER.
